HAIR CURLER

Filed Feb. 21, 1929

UNITED STATES PATENT OFFICE

HAROLD W. FERGUSON, OF ROCHESTER, NEW YORK

HAIR CURLER

Application filed February 21, 1929. Serial No. 341,594.

This invention relates to hair curlers and especially to that class of hair curlers employed for what is known as permanent waving. An object of this invention is to provide a construction in which the hair on the bobbin has steam jets forcing steam directly into the curled hair throughout the length of the desired curl so that an even curling action is obtained.

10 To this and other ends, the invention consists of certain parts and combinations of parts, all of which will be hereinafter described: the novel features being pointed out in the appended claims.

15 In the drawings:

Fig. 1 is a side elevation of a hair curler constructed according to one embodiment of the invention;

20 Fig. 2 is a longitudinal section of the same;

Fig. 3 is a rear elevation;

Fig. 4 is a section on the line 4—4, Fig. 2;

Fig. 5 is a section on the line 5—5, Fig. 2; and

25 Figs. 6 and 7 are detail views of the clamp for constricting the tubular end piece carrying the heat shield.

The apparatus illustrated, comprises an outer steam casing 1 and an inner bobbin casing 2 extending longitudinally therethrough, 30 open at its ends and of smaller diameter than the outer casing to provide an annular chamber 3 therebetween. The inner casing is secured in the outer casing by soldering or other suitable means and projects beyond its ends. A partition 4 in the outer casing forms 35

a suitable source of steam supply containing, if desired, a hair softener, such as ammonia etc. The partition or wall 4 is provided with a plurality of circumferentially arranged openings or ports 7 through which 40 the steam is permitted to pass to the chamber 3. Within the chamber 3 the wall of the inner casing is provided with a plurality of openings or perforations 8 through which

45 the steam or vapor is forcefully jetted directly onto the wound hair throughout the 50

length of the steam chamber or throughout the desired curl.

The lock of hair to be operated on is wound on a bobbin 9^a and inserted in the inner casing from the end adapted to be nearest the head of the patient and which has a flexible tubing 10 of rubber or other suitable material connected therewith and adapted to be clamped closely about the lock of hair to prevent the escape of steam onto the head of the patient. To further protect the head of the patient from the heat of the steam, a cap or scalp shield 11 of rubber or other suitable material may be secured in, or made integral with, the free end of the tubular member 10. It will be noted that live steam entering the chamber 3 expands and forms a pressure therein forcing it inwardly through the openings or perforations 8 in the form of a plurality of streams or jets 55 which play on the lock of hair on the bobbin within the casing.

60 Means are provided for clamping the tubular member 10 tightly about the lock of hair 65 to prevent the escape of steam or water 70 formed by its condensation from the tubular member to the head of the patient. To this end, a support 12 extends from the outer casing to a point conveniently beyond the end of the inner casing and has suitable clamping devices mounted thereon. Said clamping devices comprise a pair of curved jaws 75 80 85 90 95 100 13 and 14 pivoted on the support 12 and having finger pieces 15 and 16 at their free ends. Locking devices are provided for locking the jaws in clamping engagement with the outer wall of the tubular member. To this end, the jaw 14 is provided with an extension 17 in the form of a finger piece and has a pair of upstanding lugs 18 thereon in which is pivotally mounted a locking member 19 having a detent 20 at one end adapted to project through an opening in the jaw 14 and into engagement with one or another of a plurality of openings 21 in the jaw 13. A spring 22, arranged between the locking member 19 and the jaw 14, serves to maintain the locking member in locking engagement with the jaw 13. A finger piece 19^a is provided for releasing the lock.

In using the curler, a lock of hair to be operated on is properly wound on the bobbin 9^a and secured thereto by any suitable means, as a cord, and the bobbin with the hair is then inserted through the tubular member 10 into the inner casing 2. The bobbin has sufficient length to project from the opposite end of the casing which has a cap 20^a of rubber or other suitable material having a central opening through which the bobbin extends to center the latter and is so formed as to permit the escape of steam. The flexible tubular member 10 is now clamped into engagement with the hair by gripping the finger pieces 15 and 16 and held in clamping engagement by the locking devices. Steam is now admitted to the chamber 5 through the duct 6 and enters the chamber 3 through the ports 7 and from thence to the inner casing 2 through the openings 8 into contact with the hair. A portion of the steam condenses in the inner tube and the chambers 3 and 5, and means are provided for draining off the liquid formed by said condensation. Said means comprises a tubular duct 21^a secured in the wall of the inner casing and extending outwardly through an opening in the wall of the outer casing and adapted to receive a tube to carry the condensed liquid to a suitable receptacle. The duct 21 may be provided with an orifice 22^a communicating with the chamber 3 to permit the escape of condensed water from said chamber. When the operation is complete, the clamping device is released by releasing its locking device and the bobbin with the lock of hair is pushed out and removed from the casings.

It will be noted that a hair curler constructed according to this invention is adapted to protect the head of the patient from the heat and condensation of the steam by means of the shield 11 and the clamping devices, both of which are conveniently mounted on the instrument itself. The chamber formed between the outer and inner casings serves to insulate the inner chamber, conserving its heat and securing a more even temperature. The drainage provided serves to prevent the accumulation of condensed steam in the casings and thus to keep the hair uniformly dry throughout the operation.

Due to the fact that the hair on the bobbin is subjected to steam jets throughout its length, the hair is effectively curled because the steam jets penetrate the hair to the bobbin. This gives an even curling action throughout. As the bobbin is not heated, the outside layer of hair is subjected to greater heat which it requires owing to its larger curl formation than that wound directly on the rod or adjacent thereto.

What I claim as my invention and desire to secure by Letters Patent is:

1. A hair curler having an outer chamber, an inner bobbin receiving chamber, means

for admitting steam to both chambers, and means for draining both chambers.

2. A hair curler having a steam chamber, a bobbin receiving chamber arranged within the steam chamber, and a drain duct extending outwardly from the bobbin receiving chamber through the steam chamber and having a port communicating with the latter to drain the latter.

3. A hair curler comprising a steam casing, a bobbin casing arranged within the steam casing, means for admitting steam to the bobbin casing from the steam casing, a steam inlet chamber, and a plurality of circumferentially arranged ports leading therefrom to the steam casing.

4. A hair curler comprising a steam casing, a bobbin casing extending therethrough and having an open end, a flexible extension on the open end of the bobbin casing, and a scalp shield on said extension.

5. A hair curler comprising a steam casing, a bobbin casing extending therethrough and having an open end, a flexible extension on the open end of the bobbin casing, and means mounted on the steam casing for clamping said extension on the hair.

6. A hair curler comprising an outer casing, an inner casing, means for admitting steam to said casings, and a common means for draining the interior of both of said casings.

7. The method of curling hair on the head which consists in curling the hair and forcing jets of steam inwardly with equal pressure into the hair and entirely around the curl and throughout the length of the curl.

8. In a hair curler, a bobbin, a bobbin receiving chamber having a plurality of jet openings surrounding the bobbin in the chamber, and means for supplying steam through said jet openings under a substantially uniform pressure.

9. In a hair curler, a hair bobbin, a hair bobbin receiving chamber having a plurality of jet openings entirely surrounding the bobbin in the bobbin receiving chamber, a chamber surrounding the bobbin receiving chamber and having a wall surrounding said bobbin receiving chamber and closing one end of the chamber, said wall having equally spaced openings to permit the steam to enter the outer chamber at points around the bobbin receiving chamber so that the pressure of the steam to all of the jet openings is uniform.

10. A hair curler comprising a casing, a flexible tubular member connected to an end of the casing, a hair bobbin insertible through the tubular member into the casing, and a clamp mounted upon and permanently connected to the casing and adapted to clamp the tubular member closely about the lock of hair wound on the bobbin.

11. A hair curler comprising a casing, a scalp shield, a flexible tubular member con-

necting the scalp shield to an end of the casing, a hair bobbin passable through the scalp shield and tubular member into the casing, clamping means on the tubular member, and
5 a positive connection between the clamping means and casing.

12. A hair curler comprising concentric casings, the inner casing projecting beyond the ends of the outer casing and having its
10 intermediate portion perforated, a partition adjacent an end of the outer casing forming a chamber, means for supplying steam to said chamber, a drain duct connecting with both casings, a cap fitted to a projecting end of
15 the inner casing, a flexible tubular member connected to the opposite end of the inner casing and provided at its outer end with a scalp shield, a hair bobbin passable through the scalp shield and tubular member into
20 and through the inner casing, clamping means on the tubular member, and a positive connection between the clamping means and the outer casing.
